PAPER ROLL HOLDER

Sven Salmenson, Stockholm, Sweden

Application May 26, 1948, Serial No. 29,223

Claims priority, application Sweden
September 1, 1945

12 Claims. (Cl. 242—55.2)

1

My invention relates to holders for paper rolls, and more particularly to such holders having an elongated member upon which apertured paper rolls are adapted to be rotatably positioned and from the outer free ends of which it is desired to tear off pieces of paper.

In holders of this type generally provided heretofore for paper rolls like toilet tissue and paper toweling, for example, the elongated supporting member is usually held in a horizontal position by a support having movable provisions for removing the tubular member of a used paper roll and positioning a fresh paper roll in place.

While a piece of paper can be torn off by one hand from the free end of a paper roll rotatably supported in a horizontal position, the desired amount of paper frequently cannot be torn off, particularly when a user applies relatively great pulling force to the free end to unwind the paper which often causes the roll to turn more than necessary due to its own momentum. Further, it is often necessary to hold the paper roll with one hand while using the other hand to tear off a piece of paper. Also, the extreme free end of a paper roll, especially toilet tissue and paper toweling, tends to cling to the next layer of paper when rotatably supported in a horizontal position which requires shifting the roll back and forth by hand to loosen the free end to make it hang from the roll.

It is an object of my invention to provide an improved holder for paper rolls which will enable a user at all times to tear off a piece of paper of desired length with one hand.

Another object of the invention is to provide such a holder for paper rolls which is of simple construction and in which no moving part or parts are required, thereby facilitating the insertion of a fresh paper roll on the holder.

A further object of the invention is to provide such a holder which occupies a minimum amount of space, essentially no greater than that occupied by the roll itself, on a wall upon which it is mounted.

The novel features which I believe to be characteristic of my invention are set forth with particularity in the claims. The invention, both as to organization and method, together with the above and other objects and advantages thereof, will be better understood by reference to the following description taken in connection with the accompanying drawing forming a part of this specification, and of which:

Fig. 1 is a front elevation of a holder for paper rolls embodying my invention;

2

Fig. 2 is a plan view of the paper roll holder Fig. 1;

Fig. 3 is a perspective view of the construction shown in Figs. 1 and 2;

5 Fig. 4 is a front elevation of a paper roll holder illustrating a modification of the embodiment shown in Figs. 1 to 3; and

Fig. 5 is a plan view of the form of holder shown in Fig. 4.

10 Referring to Figs. 1 to 3 of the drawing, a holder for paper rolls which I have shown embodying my invention includes a base or back plate 10 having openings 11 adapted to receive screws 12 or other suitable fastening members for rigidly 15 mounting the holder in position on a vertical wall 14. To the base 10 is fixed a side arm 15 which projects forwardly therefrom, such arm being at a right angle and perpendicular to the base 10 and also to the wall 14, as best seen in Fig. 2.

20 A supporting member 16 for paper rolls, which may be in the form of a round pin or rod, for example, is secured at its lower end to the bottom portion of the side arm 15 and projects obliquely upward at an angle to the vertical. As best shown

25 in Fig. 2, the supporting member 16 is disposed in a plane which is parallel to the base 10 and wall 14, the gap or space between the supporting member and base determining the maximum size paper roll that can be accommodated by the holder.

In using the holder illustrated in Figs. 1 to 3 and just described, a roll of paper 17, which is shown in dotted lines, is slipped over the supporting member 16. The apertured paper roll 17 may

30 be paper toweling which is perforated and absorbent in character. Since the upper end of the supporting member 16 projects freely into space and is unobstructed by any fastening provisions, it is only necessary to slip the hollow tube, upon

35 which the paper roll is usually wound, over the supporting member to ready the paper holder for use. The paper roll 17 is retained in position simply by its own weight, and, as will be described

40 presently, cannot be inadvertently removed from the supporting member 16 in normal use of the holder. The paper roll is positioned on the supporting member 16 so that the free end thereof

45 will extend downwardly from the side 17a of the roll which is removed from the base 10. Hence, the free end of the paper roll is always easily accessible.

50 It will be seen in Figs. 1 to 3 that, when the paper roll is positioned on the supporting member 16, the uppermost region at the lower end

thereof bears at 18 against the surface 19 of the side arm 15.

The desired length of paper is unwound from the paper roll 17 by grasping the free end thereof and pulling it away from the base 10 and wall 14 and in a direction which is more or less perpendicular to the axis of the supporting member 16, as indicated by the arrow A in Fig. 2. The paper roll 17 tends to move slightly upward on the supporting member 16 when the pulling force is applied more or less perpendicular to the axis thereof, so that the lower end of the paper roll at the region 18 will be free a considerable part of the time from the surface 19 of the side arm as the paper is being unwound. Such pulling force need not be applied precisely normal to the axis of the supporting member but is preferable because, when the paper is unrolled in this manner, the frictional engagement at 18 between the lower end of the roll and the surface 19 at the region 18 is at a minimum. Even when the pulling force at the free end of the paper is applied at an angle which is slightly less than a right angle to the axis of the supporting member 16, the frictional engagement of the paper roll 17 against the surface 19 is not too great when such pulling force is in a downward direction. Further, when such pulling force is slightly upward, the paper roll cannot be readily removed from the supporting member 16 although the paper roll is freely movable in its lengthwise direction thereon and not locked or clamped in position.

After the desired length of paper is unwound from the paper roll, the direction of the pulling force applied to the free end thereof is shifted downwardly, as indicated by the arrows B in Figs. 1 and 2, in order to produce maximum frictional engagement at 18 between the paper roll and the side arm 15. In this manner the paper roll is more or less clamped in position and prevented from freely turning on the supporting member 16, such clamping action being due to the upwardly oblique position of the supporting member with respect to the side arm 15. The pulling force applied to the unwound section of the paper roll initially causes the latter to bear against the side arm 15 to prevent free turning movement of the paper roll, and, with continued application of such pulling force, the unwound length of paper is readily torn from the paper roll. When the paper roll is perforated, the tearing action tends to occur at a perforated region of the roll since such regions are the least resistant to tearing. However, even when the paper is not perforated and in the form of a continuous sheet, the paper will tear readily in the manner just described due to the fact that the paper roll is more or less clamped or locked in position and the upper free edge of the unwound portion of the paper is subjected to pulling force of considerable magnitude.

The side arm 15 is desirably of such height that, when a paper roll is positioned on the supporting member 16, the lower end of the roll will always bear against successively lower regions of the arm as the paper is being consumed and the outer diameter of the paper roll becomes smaller. The supporting member 16 preferably should project obliquely upward at a suitable angle, such as, for example, at an angle from 45° to 60° from the vertical. When the holder is to be used for paper toweling of the type which is now available, the supporting member 16 is positioned such a distance from the vertical plane of the base 10 that the space therebetween will

nicely accommodate the paper towel roll and provide sufficient clearance to enable the paper roll to be readily positioned on the supporting member. With such construction of the paper roll holder, a compact arrangement is provided and the holder and paper roll positioned thereon will occupy a minimum amount of space on the wall upon which it is mounted.

In Figs. 4 and 5 I have shown a modification of the embodiment just described in which the paper roll holder includes a circular base or mounting plate 19a having openings 19a adapted to receive screws 12a for fastening the holder to a vertical wall 14a. To the base 19a is fixed one end of a rod 20 which includes an end portion 15a projecting outwardly from the base, an intermediate portion 19a extending downwardly from the outer end of the end portion 15a, and the opposite end portion 21 which projects obliquely upward from the lower end of the intermediate portion 19a. The lower end of a round pin 16a is recessed to receive the upwardly projecting end portion 21 of the rod 20.

In the modification of Figs. 4 and 5 the intermediate rod portion 19a performs the same function as the surface 19 of the side arm 15 in the embodiment first described. While the side arm 15 in Figs. 1 to 3 provides a surface 19 which is substantially vertical and against which the paper roll is adapted to bear, the intermediate rod portion 19a in Figs. 4 and 5 is at an angle to the vertical. However, in both forms of the invention shown the supporting members 16 and 19a are at an acute angle with respect to the part of the holder against which the lower end of the paper roll is adapted to bear. In Figs. 4 and 5 the uppermost region at the lower end of the paper roll 17a, indicated by dotted lines, bears at 18a against the intermediate rod portion 19a, and it is at this region that the clamping action is produced when pulling force is applied to the free end of the paper roll to tear off a piece of paper in the manner previously described in connection with the first embodiment.

While the supporting member for the paper rolls may extend obliquely upward at an acute angle of at least 30° from the vertical, I have found out in practice that it is preferable to mount the supporting member at an angle in a range of about 45° to 60° from the vertical. With such inclination of the supporting member the upper and lower extremities thereof are disposed in spaced apart planes transverse to the vertical wall. When pulling force is initially applied to the outer free end of a paper roll to unwind paper therefrom, such pulling force is applied in such a manner that the predominant component of the force is in a direction perpendicular to the longitudinal axis of the supporting member, so that the frictional engagement between the roll and surface against which it bears at the regions 18 and 18a will be insufficient to retard turning movement of the roll. Thereafter the pulling force is shifted in such a manner that the predominant component thereof is in a direction toward the surface or regions 18 and 18a, so that the frictional engagement between the roll and such surface will be adequate to prevent turning movement of the roll and enable a piece of paper to be torn off the roll by the pulling force.

The modification of Figs. 4 and 5 provides an extremely simple construction of holder for paper rolls which is neat in appearance. When a paper roll is positioned on the supporting member 16a, the only parts of the holder which are visible are

the bent rod 20 and circular-shaped base 10a to which it is fixed. In both the embodiment of Figs. 1 to 3 and the modification of Figs. 4 and 5, the holders are of inexpensive construction because of the absence of any moving parts which are usually necessary in a conventional type of holder in which the paper roll is supported in a horizontal position between spaced apart end members.

In the embodiment of Figs. 1 to 3 the base 10 and side arm may be formed of metal or wood, or molded in a single piece from synthetic resinous material. The supporting member 16 may be formed of wood or any other suitable material. The base 10a and rod 20 in the modification of Figs. 4 and 5 may be formed of steel or other suitable material possessing adequate strength to provide a rigid support for the paper roll holder. When formed of suitable metal, the rod 20 is bent to the desired shape and the extreme end of the end portion 15a may be fixed, as by brazing, for example, in a central aperture provided in the base 10a. In order to facilitate mounting holders on a wall so that the elongated supporting member will extend obliquely upward at the proper angle, the base may be marked by an arrow, like the arrow C in Fig. 4, for example, which should point upward when the holder is mounted on a wall. Further, the elongated supporting member may extend obliquely upward either to the left or right from the vertical.

In view of the foregoing, it will now be understood that an improved holder for paper rolls has been provided which enables paper to be unrolled in any desired length in a convenient manner. In both embodiments the elongated supporting members 16 and 16a, respectively, are mounted on a vertical wall in such a manner that each supporting member is inclined from the vertical in a plane substantially parallel to the vertical wall upon which it is mounted. Stated another way, each supporting member is inclined from the vertical and extends across the vertical wall in a horizontally extending direction with the upper and lower extremities at the longitudinal axis thereof intersecting spaced apart parallel vertical planes, respectively, which are transverse to the vertical wall. In accord with the invention the supporting structures of the holders described above include surface portions 18 and 18a, respectively, which are removed and spaced from the vertical walls upon which the holders are mounted and constitute the only regions or places against which a peripheral edge of the lower end of the roll is adapted to bear. After a desired length of paper is unrolled by grasping the free end and pulling such free end outwardly from the wall in the direction of the arrow A, it is not necessary to release the free end but only to shift the direction of the pulling force in the direction of the arrow B to produce the tearing action. Hence, it is not necessary in using the above described holders for paper rolls to hold a roll with one hand to prevent turning movement thereof while the other hand is employed to tear off a desired section of unrolled paper from the roll, so that a minimum amount of effort is required on the part of a user to tear off pieces of paper from paper rolls. Moreover, in the improved holder described above, the clamping action is effected at 18 and 18a, respectively, at the lower end of the paper roll irrespective of the quantity of paper remaining on the roll.

The desired braking action imparted to the paper roll, when tearing of a section thereof is

being effected, may be effected in several ways. For example, axial movement may be imparted to the paper roll so that it will bear against the outer surface of a conical-shaped element or a recess in an element which is conical-shaped, the axes of such elements being in alignment with the axis of the supporting member. Such recess of conical shape may be incorporated as a part of the supporting member for the paper roll, or a conical-shaped enlargement may be provided at the lower end of the supporting member adapted to frictionally engage the lower end of the paper roll at the region defining the central aperture thereof. The supporting member for the paper rolls may also be provided with one or more suitable edges adapted to cooperate with a paper roll, either at the central aperture or outer peripheral portion thereof, and adapted to engage and lock the roll in a fixed position when downward movement is imparted to the paper roll on the supporting member. Such locking action may be effected independently of or in conjunction with the braking effect accomplished in the embodiments described above.

This application is a continuation-in-part of my application Serial No. 693,756, filed August 29, 1946, which now is abandoned.

While I have shown and described several embodiments of the invention, it will be apparent from the foregoing that various modifications and changes may be made without departing from the spirit and scope of the invention, as pointed out in the following claims.

What is claimed is:

1. A holder for paper rolls comprising an elongated supporting member upon which a paper roll can be rotatably positioned, means cooperating with the lower end of said member adapted to mount the latter on a wall in spaced relation thereto so that said member is inclined at an acute angle from the vertical and extends across the wall in a horizontally extending direction with the upper and lower extremities at the longitudinal axis thereof intersecting spaced apart vertical planes, respectively, which are essentially parallel to one another and transverse to the wall, and structure embodied in the holder providing a surface at a region which is removed from the wall and against which a lower portion of the roll is adapted to bear, said structure being so constructed and formed that the frictional engagement between the roll and said surface is relatively small and will enable the roll to be turned when the outer free end thereof is grasped and pulled outwardly from the wall in a direction more or less at a right angle to the axis of said member and normal to the wall, and the frictional engagement between the roll and said surface is relatively great and tends to prevent turning movement of the roll when the outer free end thereof is pulled downwardly to facilitate tearing off a piece of paper.

2. A holder for paper rolls comprising an elongated supporting member upon which such a paper roll can be rotatably positioned, structure cooperating with the lower end of said member adapted to mount the latter on a wall in spaced relation thereto so that said member is inclined from the vertical and extends across the wall in a horizontally extending direction with the upper and lower extremities at the longitudinal axis thereof intersecting spaced apart parallel vertical planes, respectively, which are transverse to the wall, and said structure including a surface at a place which is removed from the wall and

constitutes the only region against which a peripheral edge of the lower end portion of the roll is adapted to bear, said structure being so constructed and formed that the frictional engagement between the roll and said region is relatively small and will enable the roll to be turned when the outer free end thereof is grasped and pulled in a direction more or less at a right angle to the axis of said supporting member, and the frictional engagement between the roll and said region is relatively great and tends to prevent turning movement of the roll when the outer free end thereof is pulled downwardly to facilitate tearing off a piece of paper.

3. A holder for apertured paper rolls comprising an elongated supporting member having an unobstructed upper end over which such a paper roll can conveniently be rotatably positioned, means cooperating with the lower end of said supporting member adapted to mount the latter on a wall in spaced relation thereto so that said member is inclined from the vertical in a plane substantially parallel to the wall with the upper and lower extremities of said member disposed in spaced apart planes transverse to the wall, and structure embodied in the holder providing a region against which a lower portion of the roll is adapted to bear, said structure being so constructed and formed that the frictional engagement between the roll and said region is relatively small and will enable the roll to be turned when the outer free end thereof is grasped and pulled outwardly from the wall in a direction more or less at a right angle to the axis of the supporting member and the wall, and the frictional engagement between the roll and said region is relatively great and tends to prevent turning movement of the roll when the outer free end thereof is pulled downwardly to facilitate tearing off a piece of paper.

4. For use on a vertical wall, a holder for apertured paper rolls comprising an elongated supporting member upon which such a paper roll conveniently can be rotatably positioned, and structure cooperating with the lower end of said member adapted to mount the latter on the wall in spaced relation thereto so that said member is inclined from the vertical and extends across the wall in a horizontally extending direction with the upper and lower extremities at the longitudinal axis thereof intersecting spaced apart parallel vertical planes, respectively, which are transverse to the wall, and said structure including an element forming an acute angle of less than 90° with said member and having a surface at a place which is removed from the vertical wall and constitutes the only region against which a peripheral edge of the lower end of the roll is adapted to bear, said structure being so constructed and formed that the frictional engagement between the roll and said region is relatively small and will enable the roll to be turned when the outer free end thereof is grasped and pulled outwardly from the wall in a direction more or less at a right angle to the axis of said member, and the frictional engagement between the roll and said region is relatively great and tends to prevent turning movement of the roll when the outer free end thereof is pulled downwardly to facilitate tearing off a piece of paper.

5. A holder for apertured paper rolls from the outer free ends of which it is desired to tear off pieces, said holder comprising an elongated supporting member upon which a paper roll conveniently can be rotatably positioned, and struc-

ture cooperating with the lower end of said member adapted to mount the latter on a vertical wall in spaced relation thereto so that said member is inclined from the vertical and extends across the wall in a horizontally extending direction with the upper and lower extremities at the longitudinal axis thereof intersecting spaced apart parallel vertical planes, respectively, which are transverse to the wall, said structure including an element projecting upwardly from the lower end of said member and having at least a portion thereof in substantially the same vertical plane therewith, said element providing a surface at a place which is removed from the vertical wall and constitutes the only region against which a peripheral edge at the lower extremity of the paper roll is adapted to bear, said structure being so formed and arranged that the frictional engagement between the roll and said region is relatively small and will enable the roll to be turned when the outer free end thereof is grasped and pulled outwardly from the wall in a direction more or less at a right angle to the axis of the supporting member, and the frictional engagement between the roll and said region is relatively great and tends to prevent turning movement of the roll when the outer free end thereof is pulled downwardly to facilitate tearing off a piece of paper.

6. A holder for paper rolls comprising an elongated supporting member upon which such a paper roll can be rotatably positioned, and structure cooperating with the lower end of said member adapted to mount the latter on a vertical wall in spaced relation thereto so that said member is inclined from the vertical and extends across the wall in a horizontally extending direction with the upper and lower extremities at the longitudinal axis thereof intersecting spaced apart parallel vertical planes, respectively, which are transverse to the vertical wall, said structure including an element extending upwardly from the lower end of said member and forming an acute angle of less than 90° therewith to provide a region which is removed from the vertical wall and constitutes the only place against which a peripheral edge at the lower end of the roll is adapted to bear.

7. A holder as set forth in claim 6 in which said supporting member forms an acute angle in the neighborhood of about 30° to 60° from the vertical when mounted on the wall by said structure.

8. A holder for apertured paper rolls from the outer free ends of which it is desired to tear off pieces, said holder comprising an elongated supporting member upon which a paper roll can be rotatably positioned, and structure cooperating with the lower end of said member adapted to mount the latter on a wall in spaced relation thereto so that said member is inclined from the vertical in a plane substantially parallel to the wall, and said structure including an element having at least a portion thereof spaced from and in vertical alignment with said member, said element extending upwardly from the lower end of said member and forming an acute angle therewith to provide a region against which a lower portion of the roll is adapted to bear.

9. A holder as set forth in claim 8 in which said supporting member forms an acute angle in the neighborhood of about 45° to 60° from the vertical when mounted on the wall by said structure.

10. A holder for paper rolls having a central aperture and from the outer free end of which it is desired to tear off pieces, said holder compris-

ing an elongated supporting member upon which a paper roll can be rotatably positioned, and structure cooperating with the lower end of said member for mounting the latter on a vertical wall in spaced relation thereto so that said member is inclined from the vertical and extends across the wall in a horizontally extending direction with the upper and lower extremities thereof disposed in spaced apart planes transverse to the wall, said structure including a bent element having one end portion adapted to extend outwardly from the wall, another end portion to which the lower end of said member is fixed and an intermediate portion between the end portions which is at an angle of less than 90° with respect to such member, said intermediate portion having a surface constituting the only region against which a peripheral edge at the lower end of the paper roll is adapted to bear when said member is inclined from the vertical in its mounted position on the wall and extends across the latter in a horizontally extending direction.

11. A holder as set forth in claim 10 in which said structure includes a base of metallic material adapted to be attached to the wall and a

15

10 metal rod bent to provide said end portions and intermediate portion therebetween, said base providing a relatively extensive contact bearing surface relative to the cross-sectional area of said rod which acts against the wall when it is attached thereto.

12. A holder as set forth in claim 6 in which said supporting member forms an acute angle of at least 30° from the vertical when mounted on the wall by said structure and said element and supporting member form an acute angle with respect to one another in a range between and including 45° to 60°.

SVEN SALMONSON.
